CLAIM

The ornamental design for a bulge-type cable connector assembly, as shown and described.

DESCRIPTION

FIG. 1 is a perspective view of a first embodiment of a bulge-type cable connector assembly showing my new design;

FIG. 2 is a side elevation view thereof;

FIG. 3 is an end plan view thereof;

FIG. 4 is an opposite end plan view;

FIG. 5 is a front perspective view of a second embodiment of a bulge-type cable connector assembly showing my new design;

FIG. 6 is a side elevation thereof;

FIG. 7 is an end plan view thereof; and,

FIG. 8 is an opposite end plan view thereof.

The broken line showing of the environment is for illustrative purposes only and forms no part of the claimed design.
